CINDER NOTCH COOLER

Karl Steinbacher, Portsmouth, Ohio

Application March 5, 1938, Serial No. 194,153

3 Claims. (Cl. 122—6.6)

This invention relates to a new and improved cinder notch cooler or the like, and more particularly to a device of this character which is sectionalized in such manner that damaged portions thereof may be removed and replaced.

5 Cinder notch coolers are hollow, water-cooled castings, usually made of copper. The coolers are sometimes made in a plurality of tubular frusto-conical sections. Thus the larger element or cooler proper may support at its inner, smaller end, an intermediate cooler. This intermediate cooler may, in turn, support a smaller water-cooled member which is commonly called a monkey.

10 Cinder notch coolers are used in metallurgical furnaces and the cinder or slag flows from the furnace through the monkey, the intermediate cooler and the cinder notch cooler proper into a ladle or other receptacle. The small monkey and intermediate cooler are occasionally burned through by hot metal flowing out with the cinder. These smaller parts are less expensive than the cooler proper and may be replaced with less interference with furnace operation. At times, 15 however, the main cooler is burned by the hot metal. The entire structure must then be removed and replaced, which requires a long shutdown of the furnace, and also involves the loss of an expensive copper casting. In blast furnace operation, the replacement of a cinder notch cooler is looked upon as the most arduous work around the furnace. There have been cases where it has required many hours to make the replacement.

20 It is an object of the present invention to provide a new and improved cinder notch cooler.

It is a further object to provide such a cooler having a readily removable and replaceable portion located where it may be contacted by molten metal, should molten metal pass through the cooler.

25 It is also an object to provide a sectional cooler body in which the portions adapted to seat the intermediate cooler are all formed upon the main body of the cooler.

Other and further objects will appear as the description proceeds.

I have shown a preferred embodiment of my invention in the accompanying drawing, in 30 which—

Figure 1 is a longitudinal section through the improved cinder notch cooler assembly, with the separable section removed;

Figure 2 is a view similar to Figure 1 but showing the separable section of the main cooler;

Figure 3 is a view of Figure 1 as seen from the left, but with the separable section in place; and

Figure 4 is a view of the separable section as seen in Figure 3 but removed from the assembly. 5

The cinder notch cooler assembly comprises the main cooler or cooler proper 5, which supports the intermediate cooler 6. This intermediate cooler 6 in turn supports the innermost cooler 7, commonly called the monkey. The main 10 cooler 5 is a hollow body, frusto-conical in general shape, with a segment removed at 8. It will be noted that this segment extends from the larger end to a point adjacent the smaller end of the member 5. The smaller end of the member 5 forms a continuous circle, the end of the space formed by removing the segment 8 being closed by the hollow section 9 having a radial bearing surface 10.

15 The section 9, together with the forward end of the main body of the member 5, provides a conical seating surface 11 against which is seated a similar surface 12 formed on the outer periphery of the large end of the intermediate cooler 6. The intermediate cooler 6 is continuous and is 20 provided with an interior seating surface 13 at its smaller end against which is fitted the surface 14 of the large end of the monkey 7. The rear face of the monkey 7 is provided with the tapped 25 openings 15. Similarly the exposed rear face of the intermediate cooler 6 is provided with the tapped openings 16. The rear face of the body of the cooler is provided with tapped openings 17. It is to be understood that these various 30 tapped openings in the several castings serve both as connections for introducing and withdrawing cooling water and also for removal of the core in making the castings. The lower openings, if not used for introduction or withdrawal of cooling fluid, may be closed with plugs which 35 can be removed if desired from time to time for removal of sediment which may collect in the interior of the castings.

35 The removable and replaceable segment 18 is shown in end view in Figure 4 and in longitudinal section in Figure 2. It is also shown in place in Figure 3. This section or segment has a flat forward end 19 adapted to seat firmly and fit closely against the seating face 10 of the portion 9 of the main body 5 of the cooler proper. The 40 faces 8 of the opening in the cooler body 5 are provided with semi-circular notches 20 which are 45 provided with similar notches 21 formed in the meeting faces of the replaceable segment 18. These notches when in registration are 50 50

adapted to receive dowel pins which will maintain the parts in proper interfitting relationship. The section 18 as shown in Figure 4, is provided with the tapped openings 22, one of which may be used to introduce the cooling fluid and the other to withdraw it.

It will be understood that the assembly will be inserted so as to extend through the furnace wall with the segment 18 at the lower position 10 as shown in figures of the drawing. Thus when the cooler is used to withdraw cinder from the furnace it will pass over the movable section 18 and will normally never be in sufficient quantity of flow to engage the body of the cooler. It will 15 be understood that normally the cinder will not destroy any portions of the cooler. If, however, in the furnace operation the molten metal gets high enough so that some of it runs out with the cinder, this molten metal may cut through 20 and ruin one or more of the portions of the assembly. If it cuts through the monkey 7, that may be withdrawn and replaced with a new casting 25 without affecting the other portions of the assembly. If it should cut through the intermediate section 6, this may be removed, carrying with it the monkey which, if not damaged, may be placed in a new intermediate section and the sub-assembly restored to its position in the main body of the unit. As has been previously stated, 30 these replacements require much less loss of time and expense than replacement of the entire assembly.

Similarly, should the main cooler be cut through by the molten metal, this cutting will 35 only affect the segment 18. This segment may be readily removed without disturbing any of the other sections of the assembly. It is merely necessary to knock out the dowels extending into the notches 20 and 21, whereupon the section 40 may be readily withdrawn and a new one inserted without delay or loss of furnace time.

The construction is so designed that an integral finished surface extending throughout the whole circumference is formed on the main cooler 45 5 to receive the intermediate cooler 6. This is important in maintaining an airtight joint at this point. It also facilitates removal of the injured section when necessary.

While I have described my invention as a 50 cinder notch cooler, it will be apparent that it may also be used as a tuyère cooler. Tuyère

coolers are sometimes burned through by iron burning through blow pipes. With my improved cooler used in tuyères it would save the replacement of the entire cooler in such cases and be effective in the same manner as when used as 5 a cinder notch cooler.

Although I have described my invention with the use of copper as the material, it will be understood that cast iron is sometimes used.

The segment which is inserted may also be 10 made of cast iron, or in some cases, of refractory material, or it may be made of cast iron with a coating of refractory material on a surface where it is not desired to water cool it.

While I have shown one form of my invention, 15 this is to be understood to be illustrative only, as the invention is capable of change and modification to meet varying conditions and requirements and I contemplate such modifications as come within the spirit and scope of the appended 20 claims.

I claim:

1. A furnace wall opening hollow cooler comprising a cooler body generally frusto-conical in shape having its smaller end in the form of an 25 unbroken circle and having a hollow removable section of substantial arcuate and axial extent, said section forming a portion of the larger end of the body and meeting a radial inner face of the circular section adjacent the small end of the 30 body.

2. A furnace wall opening cooler comprising a cooler body generally frusto-conical in shape having its smaller end in the form of an unbroken circle, the inner face of said circle forming a 35 continuous seat, a second cooler member having an outer face engaging said seat, the cooler body having a removable segment extending from the large end of the body to a point adjacent the seat.

3. A furnace wall opening cooler comprising a cooler body generally frusto-conical in shape having its smaller end in the form of an unbroken circle, the inner face of said circle forming a continuous seat, a second cooler member 45 having an outer face engaging said seat, a radially extending face on a portion of the said circular portion adjacent said seat, and a removable segment of the cooler body having an end fitting against said radially extending face. 50

KARL STEINBACHER.
